CLAIM

The ornamental design for a paper cutter, as shown and described.

DESCRIPTION

FIG. 1 is a front, top perspective view of a paper cutter, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of detail "9" identified in FIG. 1. The broken lines that are immediately adjacent to the claimed areas, and contain additional broken line subject matter, depict the bounds of the claimed design, while all other broken lines are directed to environment. The broken lines form no part of the claimed design. The dash dot dash lines in FIGS. 1 and 9 are for the purpose of illustrating the enlarged view indicators and form no part of the claimed design.
